VACUUM CLEANER FLOOR TOOL ASSEMBLY HAVING A CAM ACTUATED VALVE AND AGITATOR

Dewey M. Dow, Toledo, Ohio, assignor to Air-Way
Industries, Inc., a corporation of Delaware

Application November 15, 1954, Serial No. 468,776

5 Claims. (Cl. 15—373)

This invention relates to vacuum cleaners and an object is to enable actuation of an agitator to position of use and at the same time increase the air velocity at the floor tool mouth for increasing the efficiency of the cleaning operation.

Another object is to enable concomitant actuation of the agitator and a valve for restricting the air flow and thereby increasing the air velocity and pressure head.

A further object is to produce an assembly in which turning movement of the vacuum cleaner handle or wand concomitantly advances an agitator to position of use and actuates a valve for restricting the air passage through the mouth of the floor tool, thus to cooperate with the agitator by increasing the air velocity and pressure head when the agitator is in position of use.

A still further object is to produce an assembly as above but in which both the agitator is advanced and the valve actuated or the agitator is advanced alone depending upon the direction of rotation of the wand or handle.

Other objects and advantages will hereinafter appear and for purposes of illustration but not of limitation, embodiments of the invention are shown on the accompanying drawings in which:

Figure 1 is a sectional view of a vacuum cleaner floor tool, a portion of the wand or handle being broken away;

Figure 2 is a front elevation of a portion of the floor tool;

Figure 3 is a sectional view substantially on the line 3—3 of Figure 1;

Figure 4 is a sectional view on the line 4—4 of Figure 2; and

Figure 5 is a view similar to Figure 3 in which the valve cam is altered in construction.

The illustrated embodiment of the invention comprises a vacuum cleaner nozzle or floor tool 10 in the upper portion of which is a rearwardly extending integral tubular extension 11. The floor tool has a mouth 12 which extends entirely across the same and through which dust laden air is drawn by the action of the vacuum cleaner. Such dust laden air passes upwardly through the mouth and into a tubular handle or wand 13 which connects with the vacuum cleaner which embodies the usual motor driven suction fan, dust bag and the like.

The inner end of the tubular handle 13 fits within and is fixed to a cylindrical bearing element consisting of a sleeve 14 which has an outwardly extending flange 15 at its outer end to abut against the outer end of the tubular extension 11. For retaining the tubular handle 13 in position and yet allow rotative or turning movements thereof, a spring tensioned catch 16 engages the outer face of the flange 15. In this manner, the handle 13 and tubular extension 14 may turn as a unit within the tubular extension 11 of the floor tool.

In rear of the inlet mouth 12 and extending entirely across the floor tool is a channel 17 which is open at the bottom end, and disposed within the channel 17 for vertical reciprocating movements is a brush unit having

2

a brush 18, the bristles of which are crimped and held in place by a sheet metal holder 19 which has a flat top and also extends entirely across the floor tool. The brush holder is so designed that it can slide easily within the vertical channel 17 and disposed centrally of the holder and projecting upwardly therefrom is a cam follower pin 20 which is fixed at its lower end to the holder. The upper end of the pin engages a double acting cam surface 21 which is integrally formed on the inner end portion of the sleeve 14. As shown, the cam is gently arched and the archaic form is such that turning movement of the wand or handle 13 in either direction operates to depress the pin 20 and thus advance the brush 18 to position of use with the lower end thereof projecting downwardly beyond the foot or adjacent portion of the floor tool so as to engage the surface to be cleaned. At opposite ends of the floor tool and bearing respectively in sockets 23 are coil springs 22. The upper ends of the coil springs 22 bear against the under surface of lateral extensions 24 of the sheet metal brush holder 19. Thus it will be apparent that the agitator or brush is normally urged in an upward direction or to an inoperative position out of contact with the surface or floor to be cleaned.

Extending completely across the mouth 12 of the floor tool is a plate valve 25 which has end walls 25a and a forwardly extending curved valve extension 25b adjacent its lower end. The valve has rearwardly extending surfaces 25c which incline upwardly from the ends to a central arch which constitutes a hood 29 described below. Valve 25 is pivotally supported at its ends by pivot pins 26 engaged in sockets 27 in end plates 25a, and engaging sockets in the inner ends of the floor tool. A leaf spring 28 has one end riveted to the front face of the valve and engages a portion of the floor tool to urge the valve to open position i. e. the position shown in full lines on Figure 1 with the lower end of the valve or that portion below the extension 25b engaging a ledge L of the floor tool at the edge of the mouth. In its open position, the valve provides a full open passage for air to pass into the floor tool from the surface being cleaned.

At the central portion of the plate valve is an upwardly extending hood 29 which, when the valve is in open position, has its rear edge e engaged against a shoulder s formed on the tubular extension 11 and as indicated on Figure 1. Hood 29, shown best in Figure 1 and Figure 3 is somewhat cup-shaped and has on the inside thereof a substantially V-shaped female cam follower 30 which is engageable by a V-shaped male cam 31 which projects outwardly from a plate 32 which is fixed as by welding to the inside of the sleeve 14 at the front end thereof, the cam 31 also extending forwardly beyond the front end of the sleeve 14.

It will be understood from the above description that by turning the handle or wand 13 in one direction or the other beyond an intermediate position, the brush 18 is advanced to position of use and at the same time, the valve plate is rocked to the broken line position on Figure 1, thereby greatly restricting the passage of air to the inlet mouth 12. As a result, the velocity of air drawn into the mouth and pressure head are greatly increased. This increases the cleaning action due to the higher velocity of air and the pressure head at the time that the brush is brought into operation. It will be understood that a slight play is permissible between the wand and the floor tool before the concomitant action of the brush and valve take place so that a slight turning movement in one direction or the other will not operate to actuate these parts. On the contrary, a turning movement of the handle is necessary before the parts are actuated as above described. It will also be manifest that this action takes place regardless of the direction in which the handle 13 is turned.

In the alternative form shown in Figure 5, the female single acting cam 30' is altered so that only one side is effected. In other words, only one inclined surface is provided so that in order to actuate both the brush and the valve, the handle 13 must be turned in one direction. However, turning of the handle 13 in the opposite direction operates solely to actuate the brush 18 to position of use. This makes possible the use of the brush for certain cleaning operations when it is not desired to increase the pressure head and the velocity of the air drawn in through the floor tool mouth.

Numerous changes in details of construction, arrangement and operation may be effected without departing from the spirit of the invention, especially as defined in the appended claims.

What I claim is:

1. In a vacuum cleaner, a floor tool having an inlet mouth through which dust-laden air may be drawn from the surface to be cleaned, a valve in said mouth actuatable between a position for restricting the opening from such surface thereby to increase the air velocity and pressure head and a position allowing normal air movement through the mouth, an agitator mounted in the floor tool for vertical movement, a handle, and means forming a rotatable connection between the handle and the floor tool, said means including a cylindrical bearing element which is rotatable with said handle, said cylindrical bearing element having two cams, one cam engaging the valve and the other cam engaging the agitator whereby turning of said handle actuates the valve and also the agitator.

2. In a vacuum cleaner, a floor tool having an inlet mouth through which dust-laden air may be drawn from the surface to be cleaned, a valve in said mouth shiftable between a first position for restricting the opening from such surface thereby to increase the air velocity and pressure head and a second position allowing normal air movement through the mouth, a normally spring retracted agitator mounted in the floor tool for vertical movement between extended and retracted positions, a handle, and means forming a rotatable connection between the handle and the floor tool, said means including a cylindrical bearing element which is rotatable with said handle, said cylindrical bearing element having two cams, cam follower means on the valve engaging one of the cams, cam follower means on the agitator engaging the other of said cams, and means for biasing said cam follower means respectively against said cams, the arrangement being such that turning of said handle shifts the valve to said first position and also extends the agitator.

3. In a vacuum cleaner, a floor tool having an inlet

- mouth through which dust-laden air may be drawn from the surface to be cleaned, a spring-tensioned valve in said mouth actuatable between a position for restricting the opening from such surface thereby to increase the air velocity and pressure head and a position allowing normal air movement through the mouth, a spring retracted agitator mounted in the floor tool for vertical movement, a handle, means including a cylindrical bearing element rotatably mounting said handle on said floor tool, said cylindrical bearing element rotating with the handle and having two cams, one cam engaging the valve and the other cam engaging the agitator, whereby turning of said handle actuates the valve and also the agitator.
- 15 4. In a vacuum cleaner, a floor tool having an inlet mouth through which dust-laden air may be drawn from the surface to be cleaned, a spring-tensioned valve in said mouth movable between a position for restricting the opening from such surface thereby to increase the air velocity and pressure head and a position allowing normal air movement through the mouth, a spring retracted agitator mounted in the floor tool for vertical movement, a handle, and means forming a rotatable connection between the handle and the floor tool, said means including a cylindrical bearing element having two double acting cams rotating with the handle, one cam engaging the valve and the other cam engaging the agitator whereby turning of said handle in either direction simultaneously actuates the valve and the agitator.
- 20 5. In a vacuum cleaner, a floor tool having an inlet mouth through which dust-laden air may be drawn from the surface to be cleaned, a valve in said mouth movable between a position for restricting the opening from such surface thereby to increase the air velocity and pressure head and a position allowing normal air movement through the mouth, an agitator mounted in the floor tool for vertical movement, a handle, and means forming a rotatable connection between the handle and the floor tool, said means including a cylindrical bearing element
- 25 30 35 40 45
- rotating with the handle and having two cams, one cam engaging the valve and the other cam engaging the agitator, the cam engaging the valve being single acting and the cam engaging the agitator being double acting so that turning movement of the handle in one direction advances only the agitator and in the opposite direction advances the agitator and shifts the valve to mouth restricting position.
